PUSH CATCH FOR DOORS

Filed June 29, 1927

UNITED STATES PATENT OFFICE.

THOMAS F. STUART AND HENRY A. MOORE, OF LOS ANGELES, CALIFORNIA.

PUSH CATCH FOR DOORS.

Application filed June 29, 1927. Serial No. 202,387.

Our invention relates to a latch for doors, panels, and the like, and has for its principal objects the provision of a relatively simple, practical, and easily installed latching device 5 that is released by the actuation of a push rod and which automatically moves into latching position under the influence of a spring; to provide a latch that is especially applicable for use on the doors of cupboards, closets, 10 medicine cases, bookcases, buffets, and the like; further, to provide a latch that is readily adjustable so that it may be easily and quickly installed on doors of different thicknesses; and further, to provide a latch of the character 15 referred to that may be used in connection with plain or ornamental knobs of wood, glass, metal, porcelain or composition.

Further objects of our invention are to provide a latching device that may be applied 20 to a door so as to engage or catch either beneath or on top of a shelf behind the door, or against the jamb or frame against which the door closes; further, to provide a latch that requires the boring of only one small 25 hole through the door to which the latch is applied; and further, to provide a mounting for the latch that is constructed and arranged so that no unsightly plates or screws appear 30 on the outer face of the door to which the latch is applied.

Further objects of our invention are to provide a latching device of the character referred to that may be installed without requiring any special assembly or work on the 35 part of the workman and, further, to provide an improved form of striking plate that is engaged by the bolt of the latch when the door to which the latch is applied is closed.

With the foregoing and other objects in 40 view, my invention consists in certain novel features of construction and arrangement of parts that will hereinafter be more fully described and claimed and illustrated in the accompanying drawing, in which—

Fig. 1 is a horizontal section taken through 45 a portion of a door and an adjacent portion of the door casing and showing a latch of our improved construction applied to said door.

Fig. 2 is an elevational view of the latch 50 housing.

Fig. 3 is a section taken on the line 3—3 of Fig. 2.

Fig. 4 is an elevational view of the latch 55 housing with the cover removed.

Fig. 5 is a perspective view of the latching bolt and the carrier therefor.

Fig. 6 is a perspective view of a block that is utilized for actuating a pair of toggle links within the latch housing.

Fig. 7 is a perspective view of the striking 60 plate that is associated with our improved latch.

Fig. 8 is an enlarged section taken on the line 8—8 of Fig. 4.

Fig. 9 is a sectional view showing our improved latch applied to a door and with the striking plate applied to a shelf behind the door.

Fig. 10 is a sectional view showing our improved latch applied to rabbeted doors. 70

Referring by numerals to the accompanying drawings which illustrate a practical embodiment of our invention, 10 designates a substantial rectangular housing, preferably pressed from sheet metal and having on its 75 inner side a removable cover plate 11 that is held on the housing by means of lips 12 that are bent from end walls of said housing inwardly over the end portions of said cover plate. Projecting from the sides of cover 80 plate 11 are perforated ears 13 which receive screws 14 and the latter being seated in the door or panel 15 to which the latch is applied.

Formed integral with, or fixed to cover plate 11, is an outwardly projecting externally threaded tube 16, that projects through an aperture 17 that is formed through the door 15. Screw seated on the tube 16, is a tubular member 18, that passes through a knob 19 of wood, glass, porcelain or metal and the outer 90 end of said tubular member is provided with a flange 20 that bears on the outer end of said knob.

Extending through the tubular member 18 and tube 16, is a push rod 21 having a head 95 22 on its outer end and the inner portion of said push rod extends into the housing 10 and said inner portion is threaded as designated by 23.

Arranged for sliding movement within the housing 10 is a latch bolt carrier that is preferably formed from suitable sheet metal and said carrier comprises a base plate 24 that bears against the wall of housing 10 opposite the cover plate 11 and one end of this base plate is provided with a slot 25 that connects with an aperture 26 that is formed in the adjacent wall of the housing. This slot and aperture are provided for the accommodation of the end of the push rod 21 when the latter is pushed inward to its limit of movement. 100 105 110

Projecting forwardly from one side of the base plate 24 is an arm 27, to the forward end of which is secured in any suitable manner, a short latch bolt 28 having a beveled or inclined outer face 29 and this latch bolt is arranged for sliding movement through an opening that is formed in the corresponding end wall of housing 10.

Projecting at right angles from the rear 10 end of plate 24 is a finger 30 and formed integral with the rear end of plate 24, immediately adjacent to said finger 30, is a forwardly projecting L-shaped bracket 31, in which is formed an aperture 32.

15 The inner end of a short rod 33 projects through the aperture 32 and the opposite end of said rod projects through a slot 34 that is formed in the rear end wall of housing 10 and the end of said rod outside the housing 20 is provided with a head 35. Arranged upon rod 33 between the inner end of bracket 31 and the rear end wall of the housing, is an expansive coil spring 36.

25 Pivottally connected to one of the side walls of housing 10 by means of a pin or rivet 37 is one end of an arm 38, to the free end of which is pivotally connected a relatively short substantial triangular arm 39, the outer portion of which normally bears against the inner face of finger 30. The arms 38 and 39 constitute a pair of toggle links, that are utilized in retracting the latch bolt carrier. For actuating said toggle links, we utilize a short 30 cross-bar or block 40, having in its under surface a notch 41, that receives the intermediate portion of the link or arm 38. Block 40 is provided with a centrally arranged threaded aperture that receives the threaded inner portion 23 of push rod 21 and as a result of 35 this arrangement, the position of the block 40 may be adjusted on the threaded portion of the push rod. In order to lock the block 40 to the push rod after its adjustment thereupon, a screw 42 is seated in one end of said 40 block and the inner end of which screw is adapted to clamp on the push rod.

45 In order that screw 42 may be manipulated from the exterior of the housing, a transverse slot 43 is formed in the side wall of housing 10 that is directly adjacent to the end of the block that carries said screw.

The ends of block 40 are arranged for sliding movement in transverse channels 44 that are formed in the side walls of housing 10 by 50 pressing portions of said side walls outwardly (see Fig. 4).

55 The striking plate utilized with our improved latch bolt is illustrated in Fig. 7 and said plate comprises a substantial rectangular section 45 of sheet metal, that is recessed and in the production of such plate, we prefer to turn the edges of said plate at right angles to main body portion thereof and thus the main body portion of said plate occupies 60 a plane a slight distance below the upper end

of the upturned edges, so that sufficient space is provided for the heads of the screws that are utilized in attaching the striking plate to the door casing or to a partition.

By thus recessing the body of the striking plate, the heads of the screws utilized in attaching same do not project beyond the outer surface of the plate or that surface represented by the outer edges of the upturned portions of marginal flanges.

70 One of the bent edges of the striking plate is substantially wider than the others and this wider flange or upturned portion projects from the plate so as to be engaged by the projecting end of the latch bolt 28.

75 In order that the striking plate may be readily adjusted when secured to the door casing or to a shelf or adjusted so as to compensate for shrinkage of the door casing, the 80 openings 46 in the body of the plate that receive the screws are in the form of short slots, two of which are transversely arranged, and the central one occupying a longitudinal position at or near the center of said plate (see Fig. 7). In Fig. 9, the striking plate 45 is 85 positioned on the under side of a shelf with the wide flange in front so as to be engaged by the latch bolt 28 when the door is closed.

90 In Fig. 10 the latch housing 10 is shown positioned on the inside of a rabbeted door 95 adjacent to the edge thereof and the striking plate 45 is positioned on the adjacent edge of the other door.

95 When the door or panel to which our improved latch is applied, is closed, the beveled 100 face 29 and latch bolt 28 strikes against the outwardly projecting flange of the striking plate 45 and said bolt and its carrier comprising plate 24 and parts associated therewith, will move rearwardly within the housing 10, thereby compressing spring 36, and as soon as the end of the latching bolt passes the outer portion of the striking plate, the 105 power stored in said spring 36 will act to instantly move the bolt and bolt carrier forwardly through the housing, so that said bolt is positioned behind the striking plate as illustrated in Fig. 1, under which conditions, the door will be effectually latched in 110 closed position.

115 To release the latch, knob 19 is engaged by the fingers and the thumb is pressed against head 22 of push rod 21, thereby forwarding said rod inwardly through the tubes 16 and 18. This movement carries block 40 120 to bear on the intermediate portion of link 38, thereby swinging the same on its axis 37, and the springs 38 and 39 will tend to assume a straight line position with the result that length 39 bearing on finger 30 will 125 move the bolt carrier rearwardly through the housing against the resistance offered by spring 36, and when the end of the latching bolt has been retracted so that it will clear the striking plate, the door may be readily 130

opened by an outward pull-up knob 19. As soon as pressure upon the push rod 22 is relieved, the actuated parts will return to their normal positions under the influence of 5 spring 36.

A drop latch of our improved construction is comparatively simple, may be easily and quickly applied to a door or like swing panel, is capable of being easily and quickly adjusted so as to be positioned on doors of varying thicknesses, and owing to the size of toggle links for actuating the latching bolt carrier, the bolt may be retracted so as to clear 10 the striking plate with a comparatively short 15 inward movement of the push rod.

All parts of the latch with the exception of the push rod are contained within the housing, which is an advantage in assembling, packing and installing the latch. The installation of said latch requires the boring of but 20 a single hole in the door or swinging panel.

It will be readily understood that minor changes in the size, form and construction of the various parts of our improved latch 25 may be made and substituted for those herein shown and described, without departing from the spirit of our invention, the scope of which is set forth in the appended claims.

We claim as our invention:

30 1. In a push catch for doors, a housing adapted to be positioned on a door, a spring-pressed latch bolt arranged for sliding movement within said housing, a pair of toggle links arranged within said housing, one of 35 which links is pivoted to said housing, the other link bearing on a part of the sliding latch bolt, a push rod associated with said housing for actuating said toggle links, a block adjustably mounted on said push rod

and arranged within the housing, and transversely disposed guideways formed in the top and bottom of said housing for said adjustably mounted block. 40

2. In a push catch for doors, a housing, a spring held member arranged for sliding movement therein, a latch bolt carried by said member and projecting through an opening in the end of the housing, a pair of toggle links within the housing, one of which links is pivotally connected to said housing, 45 the other link bearing on a part of the sliding latch bolt carrier, a push rod associated with said housing for actuating said toggle links, a block adjustably carried by said push rod and arranged within said housing, guideways for the ends of said block, and said block being provided with a notch which receives the toggle link with which said block engages. 50

3. In a push catch for doors, a housing, a longitudinally adjustable, tubular member carried by said housing and adapted to extend through the door to which housing is connected, a push rod extending through said tubular member, a spring held member arranged for sliding movement within the housing, a latching bolt carried by said sliding member, a pair of toggle links arranged for operation within the housing, one of which links bears on a part of said sliding member, 60 and a member adjustably mounted on the inner portion of the push rod for engaging one of said toggle links. 65

In testimony whereof we affix our signatures.

THOMAS F. STUART.
HENRY A. MOORE.
